UNITED STATES PATENT OFFICE.

YUICHI OKAMOTO, OF TOKYO, JAPAN, ASSIGNOR, BY MESNE ASSIGNMENTS, TO MORKRUM-KLEINSCHMIDT CORPORATION, OF CHICAGO, ILLINOIS, A CORPORATION OF DELAWARE.

PERFORATOR.

Application filed February 4, 1924. Serial No. 690,498.

To all whom it may concern:

Be it known that YUICHI OKAMOTO, a subject of the Emperor of Japan, residing at Tokyo, Japan, has invented certain new and useful Improvements in Perforators, of which the following is a specification.

The present invention relates to improvements in keyboard perforators.

More particularly, the invention relates

- 10 to a perforator for telegraphic and like purposes in which code combinations are perforated in tape which is then used to control automatic transmitters. A perforator of this character is disclosed in U. S. Patent No. 1,085,985 issued to Edward E. Kleinschmidt, February 13, 1914, and the preferred embodiment hereinafter disclosed will be set forth as applied to the perforator disclosed in the said patent, so much only 20 of the old structure being shown as will be necessary for an understanding of the present improvement to be had.

An object of the invention is to increase the number of combinations which may be 25 perforated on the mechanism without increasing the number of keys on the keyboard.

Other objects of the invention are such as 30 will appear in the following detailed disclosure of the preferred embodiment of which—

The drawing is a fragmental side elevation, more or less in diagram and with parts omitted to clearly set forth improvement and its relation to the old structure.

- 35 Referring to the drawing, the same reference characters are used for similar parts as has been applied thereto in the above mentioned patent and the old parts will be first described. 1 represents the key bars which are fulcrumed about bar 2, it being understood that a bank of keys are used. Arranged longitudinally of and beneath each key bar is a notched bar 3 fulcrumed 40 on transverse bar 4, and retained in normal upward position by a spring 5 individual to each notched bar 3, secured upon each key bar 1 are guide plates 6 between which bars 3 rest to prevent sidewise movement thereof. Each bar 3 has a short projecting section of its upper edge to pass between the guide plates as shown. A transversely extending stop 7 limits the downward movement of bars 3 when depressed by the key

bar, and a stop 7' limits the upward movement of the key bars. J or selector bars 8 are arranged in the manner shown in Patent No. 1,085,985 and control the punch selectors and mechanisms in the manner set forth in said patent, so that depression of any bar 8 causes a corresponding punch to be operated.

The apparatus so far described is old and shown in the above mentioned patent. No further details thereof need be described. 65 The block supporting fulcrum 4 instead of being rigidly secured to the frame work is pivotally mounted by means of pin 9 in a manner to shift bars 3 bodily with relation to bars 8 and key bars 1. Secured to extension 10 of the fulcrum block is a spring 11 which holds the fulcrum 4 together with bars 3 in rearward position or to the right in the drawing. Rigidly secured to the fulcrum block is a shift key bar 12 which when 70 depressed will throw the fulcrum 4 together with bars 3 forward. In the rearward position of key bars 3 a group of projections 13 thereof will be directly over bars 8 and projections 14 will be between bars 8 so that 75 when the keys are depressed projections 13 only will set combinations of punches. With 80 shift-bar 12 raised, only projections 14 will set punches when a key is depressed. It will of course be understood that the arrangements and numbers of projections 13 are varied on each key bar in a manner to 85 set up the various desired combinations.

In order to prevent the interference of bars 8 with the shifting movements of the 90 bars 3, stop plates 15 are provided which limit the upward movement of bars 8 and prevent engagement of teeth 13 and 14 therewith when keys 1 are in normal upper position.

By utilizing the described arrangement it will be seen that each key will perforate 2 or more characters depending on the number of shift positions provided. Such perforators are particularly adapted for perforation of code arrangements for Japanese and like alphabets where a relatively great number of different characters must be perforated.

Having described a preferred embodiment 105 of the invention what is desired to be secured by Letters Patent and claimed as new is:

1. A perforator comprising a plurality of punch controlling selectors, a plurality of members arranged to control such punch selectors in varying combinations, and means for shifting said members with relation to said punch selectors in a manner to change the combinations controlled by said members.
2. The combination as set forth in claim 1 in which said members comprise projections arranged to set said punch controlling members in different combinations in each position thereof.
3. The combination as set forth in claim 1 in which said last mentioned means comprises a pivoted fulcrum for said members.
4. A tape perforator comprising a plurality of key levers; a plurality of code combination bars each of which carries two or more code combinations and is associated with one of said key levers; and means for displacing said bars according to the code combination carried thereby which it is desired to perforate.
5. The combination as set forth in claim 4 in which said code combination bars are fulcrumed on a common member together with means for displacing said member.
6. The combination as set forth in claim 4 in which the code combination bars are pivoted on a pivoted fulcrum block, together with means for shifting said fulcrum block about its pivot.

Signed at Long Island City, New York,
this 31st day of January, 1924.

YUICHI OKAMOTO.
